ALBERT A. GORDON, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

DEVICE TO DELAY TRANSMISSION OF AN INDICATION OF WEFT EXHAUSTION.

Application filed December 11, 1925. Serial No. 74,844.

This invention relates to automatic weft replenishing box looms in which a weft detecting apparatus is operative to indicate substantial weft exhaustion in any one of 5 the several shuttles used by the loom.

In a pick and pick loom, such indications may occur for different shuttles upon two successive picks of the loom, but with certain types of weft replenishing mechanism 10 it is not desirable that the indication of weft exhaustion in two different shuttles should be transmitted to the magazine on two successive picks or forward movements of the lay.

Accordingly, it is the general object of my invention to provide means to delay the transmission of the second indication of weft exhaustion until the second forward movement of the lay after the initial indication 20 occurs. In the attainment of this object, I provide a device which renders the transmitting mechanism inoperative for one pick after each operation thereof.

My invention further relates to arrangements and combinations of parts which will be hereinafter described and more particularly pointed out in the appended claims.

A preferred form of the invention is shown in the drawings in which

Fig. 1 is a sectional side elevation of parts of a loom, taken along the line 1—1 of Fig. 2;

Fig. 2 is a front view of certain parts, taken along the line 2—2 in Fig. 1;

Fig. 3 is an enlarged plan view of the device for delaying transmission of indication;

Fig. 4 is a side elevation of the parts shown in Fig. 3 looking in the direction of the arrow 4 in Fig. 3;

Figs. 5 and 6 are views similar to Fig. 4 but showing the parts in different positions; and

Fig. 7 is a detail sectional view, taken along the line 7—7 in Fig. 3.

Referring to the drawings, I have shown 45 a loom side 10, a breast beam 11, a lay 12, and drop boxes 13 containing a plurality of shuttles S. I have also indicated a rod or shaft 14 which extends across the loom and is connected in the usual way to indicate 50 weft exhaustion to the magazine.

The parts thus far described are of the usual type and in themselves form no part of my present invention, which relates to the

devices for transmitting the indication from the weft detector or detectors to the magazine. 55

The shaft 14 is to be given an angular movement upon indication of weft exhaustion and for this purpose it is provided with an arm 15 to which is pivoted a rod or blade 16, the rear end of which may be positioned in the path of the head 17 of an actuating lever 18. This lever 18 is connected by a link 19 to a cam lever 20 provided with a cam roll 21 engaging a double face cam 22. The cam 22 is mounted upon the usual cam shaft or bottom shaft of the loom, which makes one revolution for every two picks of the loom. As the cam 22 is double-acting, the lever 20 is 60 oscillated on every pick of the loom and as 65 the lever 20 moves rearward, the head 17 of the lever 18 moves forward.

If the blade 16 is in the path of the head 17 on such forward movement, the arm 15 and shaft 14 are rocked to indicate weft exhaustion to the magazine. A spring 24 thereafter yieldingly returns the arm 15 and blade 16 to rearward position. 70

Any usual weft detecting mechanism may be utilized for placing the blade 16 in the 80 path of the head 17. I have shown in Figs. 3 and 7 a plurality of plungers 25 having bevelled ends 26 each adapted to be projected under the blade 16, raising the same into the path of the head 17. The head 17 is notched 85 at 27 (Fig. 4) to receive the bevelled rear end 28 of the blade 16.

The plungers 25 may be actuated by separate weft detectors of any usual type, mounted to co-operate with three different 90 shuttle boxes. The number of plungers and detectors will be selected to correspond with the number of drop boxes.

The particular type of weft detector forms no part of my present invention and is not 95 illustrated in detail herein, as my invention relates particularly to devices for delaying transmission of an indication of weft exhaustion from the detecting mechanism to the magazine. 100

The plungers 25 and blade 16 are supported in a bracket or stand 30 preferably secured to the breast beam 11. The blade 16 has a bearing projection 31 which rests upon a flat upper surface of the stand 30 105 when in its normal position. A stud 32 pro-

jects laterally from the blade 16 and a latch or pawl 33 is pivoted at 34 on the side of the blade 16.

A cam plate 35 is mounted on studs 36 and 37 on the side of the stand 30, the stud 36 extending through a horizontal slot 38 in the plate 35 and the stud 37 extending through a forwardly and upwardly inclined slot 39 therein. The cam plate 35 has an upward projection 40 at its forward end, a notch 41 to receive the end of the pawl 33 and an upwardly and rearwardly extended projection 42.

The blade 16 has a stud 32 extending laterally over the cam plate 35 and the pawl 33 has a stud 44 extending laterally over the blade 16 (Fig. 3). A portion of the pawl also extends laterally as indicated at 45 in Fig. 3, so that it may at times engage a fixed cam plate 46 (Fig. 4) which is secured outside of the movable cam plate 35.

Having described the details of construction of my improved delaying device, I will now describe the operation thereof.

The normal position of the parts is as shown in Fig. 4, with the rear end 28 of the blade 16 in its lower position, so that the head 17 will pass over the blade on its forward movement. Reference to Fig. 2 will show that the head 17 is offset at one side of the lever 18 to permit such movement.

If one of the plungers 25 is advanced by its weft detector, it will raise the blade 16 to the position indicated in Fig. 5, where it will be engaged by the head 17 and will be forced forward to the position indicated in Fig. 5, at the same time rocking the arm 15 and transmitting an indication of weft exhaustion to the magazine. By this movement, it will be seen that the pawl 33 is moved forward to a position where the rearwardly extending end of the pawl can engage the notch 41 in the cam plate 35.

As the arm 15 and blade 16 are thereafter moved rearward by the spring 24 (Fig. 2), the pawl 33 will push the plate 35 rearward and after a certain amount of rearward travel the movement of the blade 35 will be accelerated by a spring 50 mounted on a stud 51 secured to the bracket or stand 30. The forwardly projecting end of the spring 50 normally rests under the cam plate as indicated in Figs. 4 and 5, but as soon as the cam plate has moved a certain distance rearward, the end of the spring 50 bears against the front end of the cam plate and gives it a quick rearward movement to the position indicated in Fig. 6.

The inclined slot 39 causes the front end 60 of the cam plate with its projection 40 to be raised under the stud 32 on the blade 16, thus lifting the blade to the operative position shown in Fig. 6 and at the same time raising the pawl 33 from its notch 41, the pawl being thereafter supported in the posi-

tion shown in Fig. 6 by the stud 44 thereof which overlies the blade 16.

If for any reason the pawl 33 is not promptly released from the notch 41 toward the end of its rearward, the laterally projecting portion 45 of the pawl will engage the fixed cam plate 46 and the pawl will thus be positively displaced from the notch 41.

With the blade 16 thus held in raised position, as shown in Fig. 6, it will be evident that the head 17 on its next forward movement will pass freely under the rear end 28 of the blade 16, so that any indication of weft exhaustion by an additional plunger 25 will not be transmitted to the magazine upon that particular pick of the loom. This forward movement of the head 17, however, serves to reset the cam plate 35 by engaging the rear end 42 of the cam plate and forcing the plate from the operative position shown in Fig. 6 to the normal inoperative position shown in Fig. 4. This restores the blade 16 to its normal position and on the next pick an indication of weft exhaustion may be transmitted.

I have thus provided mechanism by which the transmission of a second indication of weft exhaustion will be delayed until the second pick after a first indication has been transmitted. As previously stated, this is of distinct advantage with certain types of weft replenishing mechanism.

Having thus described my invention and the advantages thereof, I do not wish to be limited to the details herein disclosed otherwise than as set forth in the claims, but what I claim is:

1. In a weft replenishing pick and pick loom having a weft detecting mechanism and having means by which substantially exhausted shuttles may be presented to said detecting mechanism on successive picks of the loom, the combination of means to transmit an indication of weft exhaustion from the first substantially exhausted shuttle, thus presented to said detecting mechanism, and means to prevent transmission of a second indication upon the next succeeding pick of the loom.

2. In a weft replenishing pick and pick loom having a weft detecting mechanism and having means by which substantially exhausted shuttles may be presented to said detecting mechanism on successive picks of the loom, the combination of means to transmit an indication of weft exhaustion from the first substantially exhausted shuttle thus presented to said detecting mechanism, and means to render said transmitting mechanism inoperative for a single pick after each effective operation thereof.

3. In a weft replenishing loom having weft detecting mechanism, means to transmit an indication of weft exhaustion there-

from, and means to render said transmitting mechanism inoperative for a single pick after each effective operation thereof, said latter means comprising a regularly operated actuating member, a rock shaft to transmit indications to the magazine, an element for transmitting motion from said member to said rock shaft, and means to move said element to an inoperative position and to retain said element in such position for one pick immediately succeeding operation of said rock shaft.

4. The combination as set forth in claim 3, in which the latter means comprises a cam plate mounted upon fixed bearings and a pawl on said transmitting element effective to engage and move said cam plate to a position to disable said element.

5. The combination as set forth in claim 3 in which the latter means comprises a cam plate mounted upon fixed bearings and a pawl on said transmitting element effective to engage and move said cam plate to a position to disable said element, said cam plate having a rearwardly projecting portion engaged by said actuating member on its forward movement and being reset thereby.

6. In a weft replenishing loom having a weft detecting mechanism, means to transmit an indication of weft exhaustion therefrom and means to render said transmitting means inoperative for a single pick after each effective operation thereof, said means including a regularly moved actuating member, a transmitting element engaged thereby, said element being normally in inoperative position but being movable to operative

position by the weft detecting mechanism, and means becoming operable upon the first actuation of said element effective to move said element to an inoperative position and out of control of said weft detecting mechanism.

7. In a weft replenishing loom having a weft detecting mechanism, means to transmit an indication of weft exhaustion therefrom, and means to render said transmitting means inoperative for a single pick after each effective operation thereof, said means including a regularly moved actuating member, a transmitting blade selectively engaged thereby, a cam plate effective to move said blade to an inoperative position out of control of the weft detecting mechanism, and a pawl on said blade effective to engage and move said cam plate on transmitting movement of said blade.

8. In a weft replenishing pick and pick loom having a weft detecting mechanism and having means by which substantially exhausted shuttles may be presented to said detecting mechanism on successive picks of the loom the combination of means to transmit an indication of weft exhaustion from the first substantially exhausted shuttle thus presented to said detecting mechanism, and means to render said transmitting mechanism inoperative on the next pick following such indication of weft exhaustion and to render said transmitting mechanism again operative on the second pick following such indication of weft exhaustion.

In testimony whereof I have hereunto affixed my signature.

ALBERT A. GORDON.
